UNITED STATES PATENT OFFICE.

JAMES H. FOSTER, OF TUSCALOOSA, ALABAMA.

INK-WELL.

1,170,233.

Specification of Letters Patent.

Patented Feb. 1, 1916.

Application filed February 4, 1915. Serial No. 6,149.

To all whom it may concern:

Be it known that I, JAMES H. FOSTER, a citizen of the United States, residing at Tuscaloosa, in the county of Tuscaloosa and State of Alabama, have invented new and useful Improvements in Ink-Wells, of which the following is a specification.

This invention relates to improvements in ink wells and more particularly to a closure therefor which includes an element to normally close the opening through which the pen is dipped for the purposes of preventing evaporation of the ink, of preventing dust from entering the well, and of preventing the ink from spilling in case the well is over-turned or tipped.

The objects of the invention are to provide a simply constructed, practical, and readily operated device for efficiently serving the purposes stated.

An embodiment of the invention is illustrated in the accompanying drawings, in which:

Figure 1 is a plan view of a conventional form of ink well to which the improved closure is applied; Fig. 2 is a vertical sectional view thereof; Fig. 3 is a detail vertical sectional view of the closure device; Fig. 4 is a detail horizontal sectional view of the operating element of the closure device; and Fig. 5 is a detail perspective view of the closure device.

Similar characters of reference designate corresponding parts throughout the several views.

The ink well shown by way of example in the accompanying drawings is one which is commonly used in connection with school desks wherein the well A, in the form of a glass receptacle, is fitted within a protecting sleeve B, in turn fitted within the desk cover. The well A includes a suitable top plate C having an opening D through which the pen is dipped.

The present invention includes a plate 1 for normally closing the opening D. This plate is preferably arranged under the top plate C of the well and carries a laterally projecting arm 2 which is secured to the lower end of a vertical stem 3 journaled in the plate C. The movement of the plate 1 to uncover the opening D is effected by a partial rotation of the stem 3, which carries at its projecting upper end an operating element 4 by which it may be turned.

The invention also includes means for

positively locking or holding the plate 1 in either of its operative positions, and such means preferably includes a U-shaped groove 5 and a pin 6 engaging in said groove, the said groove and pin being provided on companion, respectively, stationary and movable elements of the device. In the embodiment shown, the operating element 4 has an inverted cup-shape and is fitted over a boss 7 formed rigid with the plate C and projecting from the upper face thereof. The boss 7 is provided with the U-shaped groove 5 aforesaid and the cup-shaped knob 4 carries the aforesaid pin 6 which engages in said groove. The structure is completed by a spiral spring 8 which surrounds the stem 3 within the knob 4 and has one end secured to the boss 7 and the other end secured to said knob. The spring 8 acts both with expansive and torsional effect. By virtue of the expansive action of the spring 8 the plate 1 is held against the under surface of the plate C in either position of the stem 3 wherein the pin 6 alines with a vertical leg of the groove 5. By virtue of this action of the spring 8 under the circumstances stated, the plate 1 will be securely held against the under face of the plate C and, hence, when alined with the opening D will effectively close said opening; and, before the plate 1 can be moved laterally in either direction, i. e., either toward or away from the opening D, the element which carries the pin 6, in the embodiment shown, the knob 4, must be depressed. In this way, accidental movement of the plate 1 about the stem 3 as an axis is prevented and said plate is positively held or locked in either of its operative positions. The spring 8 by virtue of its torsional action tends to move the plate 1 toward or into alinement with the opening D and it follows that, assuming the plate 1 to be distant from the opening D, the movement of said plate to a position to close said opening is automatic consequent to a movement of the knob 4 whereby to aline the pin 6 with the horizontal portion of the groove 5. In this way, the effective closure of the opening D will not be defeated through carelessness in manipulating the device, as would perhaps some times be the case if it were necessary to manually turn the stem 3 so as to bring the plate 1 into closing position.

The invention has been described in its application to ink wells in view of the fact

that such practical application thereof is probably its most meritorious one; but it will be understood that the invention is applicable to liquid containers other than ink wells where it is desired to prevent evaporation of the liquid and access of dust to the container during the periods when the container is not being used.

Having fully described my invention, I 10 claim:—

1. In combination, a liquid container having a top plate provided with an opening through which access may be had to the liquid, a closure for said opening arranged 15 below said top plate, an operating element for said closure arranged above said top plate and having movements in angular paths, said element in its movement in one path moving said closure into or out of 20 alignment with said opening, and means for preventing a movement of said element in a direction to aline or stagger said closure and said opening except after a movement of 25 said element in a direction at an angle to said first-named direction.

2. In combination, a liquid container having a top plate provided with an opening through which access may be had to the liquid, a closure for said opening arranged 30 below said top plate, an operating element for said closure arranged above said top plate and having movements in angular paths, said element in its movement in one path moving said closure into or out of 35 alignment with said opening, means for preventing a movement of said element in a direction to aline or stagger said closure and said opening except after movement of said 40 element in a direction at an angle to said first-named direction, and a spring for holding said operating element in a normal position.

3. In combination, a liquid container having a top plate provided with an opening 45 through which access may be had to the liquid, a closure plate below said top plate to normally close said opening, an operating element above said top plate having vertical and horizontal components of movement, 50 means for preventing a horizontal movement of said operating element except after a determined vertical movement thereof and connections between said operating element and said closure plate whereby the latter is 55 actuated by a horizontal movement of said element.

4. In combination, a liquid container having a top plate provided with an opening through which access may be had to the 60 liquid, a closure plate below said top plate to normally close said opening, an operating element above said top plate having vertical and horizontal components of movement, 65 means for preventing a horizontal movement of said operating element except after

a determined vertical movement thereof, connections between said operating element and said closure plate whereby the latter is actuated by a horizontal movement of said element, and a spring resisting horizontal 70 and vertical movements of said element in certain directions.

5. In combination, a liquid container having a top plate provided with an opening through which access may be had to the 75 liquid, a closure plate below said top plate to normally close said opening, an operating element above said top plate having vertical and horizontal pivotal components of movement, means for preventing a horizontal 80 movement of said operating element except after a determined vertical movement thereof, connections between said element and said closure plate whereby the latter is actuated by a horizontal movement of said element, and a spring for restoring said operating element to normal position after a horizontal movement thereof.

6. In combination, a liquid container having an opening through which access may be 90 had to the liquid, a plate to normally close said opening, an operating element having vertical sliding and horizontal pivotal components of movement, means for preventing a horizontal movement of said operating 95 element except after a determined vertical movement thereof, connections between said element and said plate whereby the latter is actuated by a horizontal movement of said element, and a spiral spring acting both 100 expansively and torsionally for restoring said operating element to normal position after a horizontal movement thereof and for effecting a horizontal movement thereof in one direction.

7. In combination, a liquid container having an opening through which access may be had to the liquid, a plate to normally close said opening, an operating element having vertical sliding and horizontal pivotal components of movement, companion relatively 110 movable parts comprising a U-shaped groove and a pin engaging therein, one of said companion parts being associated with said operating element, connections between said operating element and said plate whereby the latter is actuated by a horizontal movement of said element, and a spiral spring acting both expansively and torsionally for restoring said operating element to normal 115 position after a horizontal movement thereof and for effecting a horizontal movement thereof in one direction.

8. In combination, a liquid container having an opening through which access may 120 be had to the liquid, a plate to normally close said opening, a stem mounted in a wall of said container for rotary and axial sliding movement and carrying said plate at one side thereof, an operating knob mounted 125 130

upon said stem, a spiral spring surrounding said stem and acting with expansive and torsional effect on said knob, a pin carried by said knob and a boss formed on the wall in which said stem is mounted and projecting within said knob, said boss having a U-shaped groove in which said pin engages.

In testimony whereof I have hereunto set my hand in presence of two subscribing witnesses.
